DRYING APPARATUS

Wendell L. Martin, Cleveland, Ohio, assignor to
 The Martin Brothers Electric Company, Cleve-
 land, Ohio, a corporation of Ohio

Application July 1, 1932, Serial No. 620,351

9 Claims. (Cl. 34—26)

My invention relates to drying apparatus, and has particular reference to apparatus for use in drying hair or the hands, or the like, and a principal object of my invention is to provide a new and improved apparatus of this type.

In the drawing accompanying this specification, and forming a part of this application, I have shown, for purposes of illustration, one form which my invention may assume, and in this drawing:

Figure 1 is a vertical sectional view of the embodiment herein illustrated, portions of the supporting pedestal being broken away,

Figure 2 is a transverse vertical sectional view of said embodiment, taken on the line 2—2 of Figure 1, while

Figure 3 is a transverse vertical sectional view, taken on the line 3—3 of Figure 1.

The embodiment of my invention herein shown comprises a tubular casing 5, pivotally supported by arms 6, forming part of a supporting pedestal 7, the casing 5 tapering toward the rear, and having a rear wall 8 provided with an aperture for the passage of the shaft 9 of a motor 10 there-through, and of sufficient size for snug reception of a boss 11, forming part of the housing of the motor 10, the latter secured to the rear wall 8 by bolts 12 passing therethrough and through flanges 13 on the housing of the motor 10, the inner end of the shaft 9 of the motor 10 carrying a centrifugal fan 14 operable to draw air toward its center and discharge such air radially outward therefrom.

Supported by the forward edge of the casing 5, and secured thereto by screws 15, is a shell 16, extending into said casing in spaced relation with respect thereto and cooperating with said casing to provide an annular passage 17, and at its rear having an aperture 18 disposed axially in line with the fan 14, also extending forwardly of the forward end of the casing 5, and having secured thereto, as by a rolled seam 19, an annular flange 20 forming the forward portion of a tapered hood member 21, extending rearwardly into said shell in spaced relation with respect thereto and closed at its rear, cooperating with the shell 16 to provide an annular passage 22.

Adjacent the forward portion of the hood member 21 is provided a plurality of circumferentially spaced inlet apertures 23, covered by a screen 24 secured at the inner side of the hood member 21 by rivets 25, and providing an inlet area communicating with the passage 22, and through the aperture 18 with the passage 17.

The hood member 21 is also provided with a plurality of circumferentially spaced openings, each accommodating one end of a grommet member or a conduit pipe 26 opening into the interior of the hood member 21, through orifice 27, 5 the opposite end of each grommet member or pipe 26 being accommodated in a corresponding opening in the shell 16, and communicating with the passage 17, through orifice 28, the grommet members or pipes 26 each being provided 10 with flanges 29 at opposite ends lying against and secured to the opposite remote surfaces of the shell 16 and the hood member 21.

An annular heating coil 30 is secured to rear outer surface of the shell 16 by fasteners 31, 15 so as to lie within the passage 17 and heat the air passing therethrough.

In use, when the motor 10 and heating coil 30 are energized, a stream of air is caused to circulate through the apparatus, such air being 20 drawn partially from without the casing and passing rearwardly through the screened apertures 23, through the passage 22, and the opening 18, into the eye of the centrifugal fan 14, being thrown circumferentially outward by the 25 fan 14, and into the passage 17 where it is heated by the coil 30, passing thence through the pipes or ducts 26 back into the hood member 21, and a substantial portion of the air discharged from the orifices 27 into the hood member 21 again 30 passes into the inlet apertures 23, thus bringing about recirculation of the air passing through the apparatus, resulting in more rapid and efficient treatment and in conservation of heat energy.

It will be appreciated that the inlet area provided by the apertures 23 substantially embraces the outlet area provided by the orifices 27 of the pipes or ducts 26, and incoming air, in its passage through the apparatus, crosses over the 40 path of the outgoing air, in a manner resembling the figure 8, and hereby produces the characteristic recirculation of the air within the apparatus.

It will be apparent that the embodiment herein described accomplishes the principal object of the invention, and is adapted for uses and purposes not herein particularly referred to, and may be variously changed and modified without departing from the spirit of my invention, 50 and accordingly it will be understood that such embodiment is illustrative only, and my invention is not limited thereto.

I claim:

1. A recirculating drier, comprising: a casing 55

having a centrifugal fan mounted therein; a hood member mounted in said casing and having a cavity for the accommodation of the object to be treated, and having an inlet and an outlet communicating with said cavity; a shell interposed between said hood member and said fan and with said hood member defining a first passage in communication with the central portion of said fan, and with said casing defining a second passage about the periphery of said fan, said inlet opening into said first passage; and means leading from said second passage through said first passage into communication with said outlet.

2. Apparatus, as of the type described, for subjecting a person to the action of a stream of gaseous-like fluid, comprising: a casing, having its mouth formed to be directed toward and partially receive the object to be treated, said mouth having an inlet area and an outlet area; fluid-directing means; and fluid-circulating means cooperating with said fluid-directing means to in-draw through said inlet area an inflowing stream of fluid, along a predetermined path, and to expel said fluid in an outflowing stream, along a predetermined path, and through said outlet area, the path of one stream intersecting the path of the other stream; said fluid-circulating means being disposed coaxially with respect to said streams; and said apparatus comprising means whereby said outflowing stream is expelled about said object, and in proximity to said inflowing stream, to be in part entrained in said inflowing stream, whereby part of said fluid is recirculated.

3. Apparatus, as of the type described, for subjecting a person to the action of a stream of gaseous-like fluid, comprising: a plurality of nested elements including an outer casing, a hood member defining a cavity for the reception of the object to be treated, and an intermediate shell member, together defining a triple-walled construction, said casing having a portion spaced from said shell to define an air passage, and said shell being spaced from said hood member to define another air passage, both of said passages communicating separately with said cavity; and fluid-circulating means communicating with both of said passages, operating to in-draw into one of said passages an inflowing stream of fluid, and to expel said fluid from another of said passages; and said apparatus comprising means whereby said fluid is expelled into said cavity about said object, and in proximity to said inflowing stream, to be in part entrained in said inflowing stream, whereby part of said fluid is recirculated.

55. 4. Apparatus, as of the type described, for subjecting a person to the action of a stream of gaseous-like fluid, comprising: a plurality of nested elements including an outer casing, a hood member defining a cavity for the reception of the object to be treated, and an intermediate shell member, together defining a triple-walled construction, said shell being spaced from said hood member to define a first air passage and said casing having a portion spaced from said shell to define a second air passage; both of said passages communicating with said cavity, and said first passage being closed at its forward extremity; and fluid-circulating means communicating with both of said passages, operating to in-draw into one of said passages an inflowing stream of fluid, and to expel said fluid in an outflowing stream from another of said passages; and said apparatus comprising means whereby said fluid is expelled into said cavity about said object, and in proximity to said inflowing stream, to be in part entrained in

said inflowing stream, whereby part of said fluid is recirculated.

5. Apparatus, as of the type described, for subjecting a person to the action of a stream of gaseous-like fluid, comprising: a casing; fluid-circulating means; a hood member and shell member defining a double-walled element disposed within said casing and having a cavity for the accommodation of the object to be treated, said element having an inlet area and an outlet area communicating with said cavity, the walls of said double-walled element defining a first passage communicating with said fluid-circulating means and with one of said areas, and with said casing defining a second passage also communicating with said fluid-circulating means; and means extending through said first passage, communicating with said second passage, and with said other area; said fluid-circulating means cooperating with said passages to in-draw through said inlet area an inflowing stream of fluid, and to expel said fluid in an outflowing stream through said outlet area; and said apparatus comprising means whereby said outflowing stream is expelled about said object, and in proximity to said inflowing stream, to be in part entrained in said inflowing stream, whereby part of said fluid is recirculated.

6. Apparatus, as of the type described, for subjecting a person to the action of a stream of gaseous-like fluid, comprising: a casing; fluid-circulating means; a double-walled hood member disposed within said casing, and having a cavity formed for the accommodation of the object to be treated, and having an inlet area and an outlet area communicating with said cavity, the walls of said double-walled hood member defining a first passage communicating with said fluid-circulating means and with one of said areas, and with said casing defining a second passage also communicating with said fluid-circulating means; and a grommet member having flanges butting the opposite outer surfaces of the walls of said hood member, and having its body portion extending through said first passage, communicating with said second passage, and with said other area; said fluid-circulating means cooperating with said passages to in-draw through said inlet area an inflowing stream of fluid, and to expel said fluid in an outflowing stream through said outlet area; and said apparatus comprising means whereby said outflowing stream is expelled about said object, and in proximity to said inflowing stream, to be in part entrained in said inflowing stream, whereby part of said fluid is recirculated.

7. Apparatus, as of the type described, for subjecting a person to the action of a stream of gaseous-like fluid, comprising: a casing; fluid-circulating means; a hood member and shell member defining a double-walled element disposed within said casing, and having a cavity formed for the accommodation of the object to be treated, said hood member having an inlet and an outlet area in the wall thereof, and communicating with said cavity, the walls of said double-walled element defining a first passage communicating with said fluid-circulating means and with one of said areas, and with said casing defining a second passage also communicating with said fluid-circulating means; and means extending through said first passage, communicating with said second passage, and with said other area; and said fluid-circulating means cooperating with said passages to in-draw through said inlet area an inflowing stream of fluid, and to expel said fluid in an outflowing stream through said outlet area; and said apparatus comprising means whereby said outflowing stream is expelled about said object, and in proximity to said inflowing stream, to be in part entrained in said inflowing stream, whereby part of said fluid is recirculated.

stream of fluid, and to expel said fluid in an out-flowing stream through said outlet area.

8. Apparatus, as of the type described, for subjecting a person to the action of a stream of gaseous-like fluid, comprising: a plurality of nested elements including an outer casing, a hood member defining a cavity for the reception of the object to be treated, and an intermediate shell member, together defining a triple-walled construction, said casing having a portion spaced from said shell to define an air passage, and said shell being spaced from said hood member to define another air passage, both of said passages communicating with said cavity, and one of said passages intersecting the other passage; and fluid-circulating means communicating with both of said passages, operating to in-draw into one of said passages an inflowing stream of fluid, and to expel said fluid from another of said passages;

and said apparatus comprising means whereby said fluid is expelled in said cavity about said object, and in proximity to said inflowing stream, to be in part entrained in said inflowing stream, whereby part of said fluid is recirculated. 5

9. A hair drying apparatus of the character described comprising an outer housing, an inner hood formed to receive the portion of the head of a patron to be dried, a shell member disposed intermediate said housing and hood to form inner 10 and outer chambers between the hood and housing, said hood having openings through its walls communicating directly with the inner chamber and communicating with the outer chamber through conduits passing through the inner 15 chamber and a fan for circulating air into and out of said hood through said chambers, openings and conduits.
